Primary Examiner — Austin Murphy(74) *Attorney, Agent, or Firm* — Peter A. Nieves;
Sheehan Phinney Bass & Green PA(57) **CLAIM**

We claim the ornamental design for a computer input device, as shown and described.

DESCRIPTION

FIG. 1 is a perspective view of a computer input device of the present invention;

FIG. 2 is a top view of the computer input device;

FIG. 3 is an underside view of the computer input device;

FIG. 4 is a front view of the computer input device;

FIG. 5 is a rear view of the computer input device;

FIG. 6 is a left side view of the computer input device;

FIG. 7 is a rear view of the computer input device;

FIG. 8 is a top view of the computer input device being worn;

FIG. 9 is an underside view of the computer input device being worn; and,

FIG. 10 is a left side view of the computer input device being worn.

The broken lines in FIGS. 8-10 are included for the purpose of showing environmental structure that forms no part of the design.
